ROTARY KILN

Niels Sofus Borch, Copenhagen, Denmark, assignor to F. L. Smidt & Company, New York, N. Y., a corporation of New Jersey

Application September 23, 1938, Serial No. 231,335

4 Claims. (Cl. 263—32)

This invention is related to rotary kiln installations, such as are employed for sintering and agglomerating purposes, and has to do more particularly with a novel device used in such an installation for directing the hot material discharging from the kiln to the outlet to the cooler.

In the treatment of finely divided materials, such as pulverulent iron ore, blast furnace dust, and the like, in sintering and agglomerating kilns, the materials, when heated to the proper temperature, become somewhat tacky so that the particles cohere and also tend to stick to the kiln lining and form crusts thereon. Such accumulations must be removed from time to time, and, accordingly, to avoid interruptions in operation, the kiln is operated in such manner that the sintering zone is short and as near the outlet end of the kiln as possible. Under such conditions, the lining in the zone of highest temperature may be kept clean by a suitable tool manipulated from outside the kiln, as, for example, by means of a water-cooled rod provided with a knife which is inserted into the kiln through the outlet end and is operated to break the crust loose.

Since the sintering zone in such kilns is immediately ahead of the discharge end, the material issuing from the kiln is very hot and tends to adhere to surfaces with which it may contact on its way to the cooler. If an ordinary hopper is used to receive the discharging material and direct it to the cooler, the interior surfaces of the hopper become caked with the material and the latter will gradually bridge across the hopper and clog the discharge opening. When this occurs, the caked material must be removed manually, and this operation is difficult and laborious because of the great heat to which the workman is exposed.

The present invention is, accordingly, directed to the provision of a novel device for receiving the hot material issuing from a kiln and directing it to a cooler, the device being so constructed that the surfaces thereof with which the hot material contacts are kept cool and chill the material so that the latter will not adhere thereto. The new device may take various forms, but ordinarily it includes a plurality of walls disposed in a hood at the discharge end of the kiln and leading to an outlet passage from the hood to the cooler. These walls are provided with cooling means which may conveniently take the form of conduits formed therein and constituting passages for a cooling medium. Such conduits may be made in various ways as, for example, by

cores placed in a mold in which the walls are cast, or the walls may be made of sheet metal forming a chamber provided with internal partitions which direct the cooling medium to all portions of the chamber.

For a better understanding of the invention, reference may be made to the accompanying drawings, in which

Figure 1 is a longitudinal section through a portion of the discharge end of a rotary kiln and its hood, the latter being constructed in accordance with the invention;

Figure 2 is a sectional view on the line 2—2 of Figure 1; and

Figure 3 is a sectional view showing a modified wall construction.

Referring to the drawings, the installation as illustrated includes a rotary kiln 10 having a lining 11 provided at its discharge end with a section 12 which enters an opening in one wall of a movable hood 13 mounted on wheels 14 on a track 15. Surrounding the opening in the hood through which the end of the kiln projects is a chamber 16 forming part of a conventional sealing device which includes an annular disc 17 contacting with the outer surface of section 12. The wall of the hood opposite to that through which the end of the kiln projects has an opening into which extends the end of a burner 18 supplied with a suitable fuel-air mixture and arranged to direct its flame into the end of the kiln.

At the lower end of the hood are mounted a pair of downwardly converging lateral walls 19 which, in the construction shown, are supported at their lower ends on hollow outlet members 20, 21, lying one upon the other and resting on a plate 22 carried by the axles 23 of wheels 14. The walls 19 are supported in inclined position at their upper ends by brackets 24 attached to the side walls 25 of the hood. Within the walls 19 are conduits 26 for a cooling fluid, each conduit having inlet and outlet connections 27, 28, respectively, which lead through the side walls 25 of the hood.

Directly beneath the end of the section 12 of the kiln is a plate 29 curved to conform to the shape of the section, and a downwardly sloping wall 30 below the plate 29 leads to the outlet opening through the members 20, 21. Both plates 29 and 30 are provided with conduits 31, 32 for the passage of a cooling fluid and these conduits have inlet and outlet connections 33, 34 leading through the side walls 25 of the hood.

The outlet member 20 is formed with a forward

extension 35 serving as a floor plate, and both this member and the member 21 are provided with internal conduits 36 for a cooling medium supplied to the conduits and withdrawn therefrom through connections not shown. The floor plate 35 serves as a means for catching discharging material which may not pass at once through the outlet passage through the members 20, 21, the material so collected forming a pile which 10 protects the plate from wear. Also, the plate facilitates removal of clinker lumps too large to pass through the outlet.

The outer end wall 25a of the hood has an opening directly above the floor plate 35, and 15 mounted in the opening is a frame 37 on which a door 38 is pivoted. The frame may, if desired, be formed with a cooling medium conduit 39 having inlet and supply connections, not shown.

20 With the construction described, the hot material issuing from the kiln passes over the surfaces of plate 29 and along the walls 19, 30, to the outlet passage formed through the members 20, 21, and the material falls through the passage 25 and through a passage 40 to the usual cooler. All the surfaces inside the hood with which the hot material may come into contact are cooled by the circulating cooling medium and these surfaces are kept at such a temperature that they 30 lower the temperature of the hot material to a point where it loses its tendency to adhere. As a result, the material passes freely through the hood and outlet passages and, accordingly, no caking up on the walls or floor of the outlet device and no clogging of the outlet occur.

In the construction shown in Figures 1 and 2, the walls and outlet members are illustrated as having conduits for the cooling medium embedded 40 therein, and such walls may readily be made by a casting operation, during which the conduits are formed by the use of cores. If desired, however, the walls may be made of sheet metal, and for this purpose, pieces of sheet metal of the proper shape and size are welded together to form a 45 chamber 41 of the desired dimensions. Before the chamber is closed, partitions 42 of sheet metal are mounted in place therein so as to provide a tortuous passage. An inlet 43 and an outlet 44 for cooling fluid are then mounted in the walls 50 of the chamber in such manner that the cooling fluid must travel through the passage from end to end from the inlet to the outlet. A sheet metal wall thus constructed serves the same purpose as those illustrated in Figures 1 and 2, and may be of considerably lighter weight.

I claim:

1. In a hood for use with a rotary kiln, the combination of a chamber having an opening through which the discharge end of the kiln projects, a horizontal floor plate at the bottom of the chamber, an outlet passage leading from an opening in the plate, a plurality of converging walls leading toward said opening, the hot material issuing from the kiln passing along the walls to the outlet passage, and passages for a cooling medium within said converging walls, floor plate, and the 10 walls of the outlet passage.

2. In a hood for use with a rotary kiln, the combination of a chamber having an opening through which the discharge end of the kiln projects, a horizontal floor plate at the bottom of the chamber, an outlet passage leading from an opening in the plate, a plurality of converging walls leading toward said opening, the hot material issuing from the kiln passing along the walls to the outlet passage, a frame surrounding 20 an opening in a wall of the chamber adjacent the floor plate, a door for the opening, and passages for a cooling medium within said converging walls, floor plate, frame, and the walls of the outlet passage.

3. In a hood for use with a rotary kiln having an opening into which the discharge end of the kiln projects, the combination of an inclined wall leading downwardly and away from said end of the kiln, a pair of walls each lying at an angle 30 to said inclined wall and converging downwardly, a horizontal floor plate below said walls having an outlet opening, the hot material issuing from the kiln passing along the inclined and converging walls to the opening, and means for cooling 35 said walls and plate.

4. A hood for use with a rotary kiln comprising walls forming a chamber into which the discharge end of the kiln projects through an opening, the chamber being mounted on wheels and movable toward and away from the kiln, and a discharge device mounted in the chamber below the end of the kiln and comprising a floor plate having an outlet therethrough for discharging material, a rear wall inclined from the end of the kiln to the floor plate adjacent the outlet, a pair of lateral walls converging downwardly to the outlet, the material issuing from the kilns moving along the walls to the outlet and the floor plate collecting material which fails to pass 40 through the outlet, and passages for a cooling medium within said walls, the floor plate, and the walls of the outlet for cooling the surfaces of the walls and plate to prevent adherence of the discharging material thereto.

NIELS SOFUS BORCH.
